RALPH OLAF HELGEBY, OF FLINT, MICHIGAN, ASSIGNOR TO A C SPARK PLUG COMPANY, OF FLINT, MICHIGAN, A COMPANY OF MICHIGAN

RATCHET-DRIVEN ODOMETER MECHANISM

Application filed February 1, 1928. Serial No. 251,145.

My invention relates to odometer mechanism of the type in which the figure wheels are driven from a ratchet wheel which is intermittently rotated by a pawl eccentrically 5 journalled on a driven shaft.

The principal object is to provide a simple and inexpensive but positive means for holding the ratchet wheel stationary while the pawl is being advanced to the next tooth on 10 the ratchet wheel. Ordinarily this is accomplished by means of a member which is spring held against the ratchet wheel and which engages the teeth. In my construction, however, this is effected by means of a 15 stamped spring member which fits snugly in a groove in the ratchet wheel and holds the latter by friction only. The advantages are that there is less wear on the ratchet teeth and the clicking noise caused by the holding 20 member sliding over the teeth is eliminated.

Other objects and advantages will be apparent upon referring to the specification and accompanying drawing, in which:

Fig. 1 is a vertical section through a speedometer showing my improved holding means for the ratchet wheel in connection therewith.

Fig. 2 is a front view of the speedometer with the face plate removed to more clearly 20 show my invention.

Fig. 3 is a perspective view of the spring stamping which serves to hold the ratchet wheel stationary while the pawl is being advanced to the next tooth.

The numeral 10 indicates a speedometer casing within which is held a frame 12. Rotatably carried in this frame is a main shaft 14 which is driven by the usual flexible shaft from the transmission or other moving part 40 of the vehicle. The upper end of this main shaft has connected to it a rotor 16 which actuates the usual speed indicating mechanism. Just below the rotor is a worm gear 18 which meshes with worm teeth 20 cut on the driven shaft 22. This shaft is rotatably supported at each end in the frame 12.

Eccentrically journalled on the shaft 22 is a pawl 24 which is held against a ratchet wheel 26 by a spring 28, the lower end of 50 which is secured about a rivet 30 fastened to

the frame 12. The ratchet wheel is rotatably mounted on a shaft 32 which is supported in the frame 12. The odometer figure wheels 34, 36, 38, 40 and 42 are also rotatably mounted on the shaft 32. The ratchet wheel is provided with a groove 44 located between the wheel proper and a flange 46. A double tooth 48 is formed on this flange and is adapted to engage a star wheel 50 once for each revolution of the ratchet wheel. This star wheel is rotatably carried on a star wheel shaft 52 which is also supported in the frame 12. The star wheel 50 is in constant mesh with a gear 54 on the figure wheel 34 and consequently the latter is moved one tenth of a revolution for each revolution of the ratchet wheel 26. The other figure wheels are each driven from the preceding one in the usual manner by star wheels 56.

It will be readily seen that as the shaft 22 is rotated, the pawl 24 will be caused to move back and forth, due to the fact that it is eccentrically carried on the shaft. When it is moved toward the left hand side of Fig. 1, it will engage a tooth of the ratchet wheel 26 and will turn the latter a part of a revolution. When the pawl is moved in the opposite direction, it is necessary to provide some means for holding the ratchet wheel stationary until the pawl has engaged the next tooth. This is accomplished by means of a stamped spring member 58 made from any suitable material, such as phosphor bronze. This member is mounted at one end upon the star wheel shaft 52 and is yoke shaped at 80 its opposite end so that it may fit into the groove 44 and straddle the central portion of the ratchet wheel where it surrounds the shaft 32. This stamped member is formed with curved portions 60 which are of greater depth than the width of the groove 44 so that when the spring member is sprung into the groove there will be considerable pressure of the stamping against the walls of the groove. Thus the ratchet wheel is held by friction 90 from turning when the pawl is being moved toward the right of Fig. 1 so that it may engage the next tooth.

Ordinarily a spring member is urged against the teeth of the ratchet wheel and 100

engages the teeth to keep the wheel from turning when the pawl is being moved to the next tooth. The disadvantages of this construction are that since the spring member is 5 constantly bearing against the teeth, the latter will be apt to become worn to such an extent that the device will not function, and also there is a noticeable clicking noise caused by the spring member sliding over 10 the teeth. It will be obvious that these objections are not encountered when using my construction, since the holding member does not operate in connection with the teeth.

It is thought from the foregoing, taken in 15 connection with the accompanying drawing, that the construction and operation of the device will be apparent to those skilled in the art, and that various changes in size, shape and proportions and details of construction 20 may be made without departing from the spirit and scope of the appended claims.

I claim:—

1. In combination, a rotatable member having a groove formed therein and carrying 25 ratchet teeth, a pawl adapted to engage said ratchet teeth for the purpose of intermittently rotating said member, and means held in said groove and adapted to frictionally engage the walls thereof for the purpose 30 of preventing rotation of said member while the pawl is being retracted.
2. In combination with a ratchet driven mechanism including a ratchet wheel having a groove formed therein, and a pawl adapted 35 to intermittently rotate said ratchet wheel, a compressible member held in said groove and adapted to frictionally engage the walls thereof for the purpose of preventing rotation of said ratchet wheel while the pawl is 40 being retracted.
3. In an odometer mechanism including a ratchet wheel having a groove formed therein, a pawl adapted to intermittently rotate said wheel, a figure wheel, a transfer 45 pinion located between said ratchet wheel and said figure wheel and adapted to rotate said figure wheel a part of a revolution for each revolution of said ratchet wheel, and a shaft upon which said transfer pinion is 50 journaled, a compressible member supported on said shaft and extending into said groove, said member being adapted to frictionally engage the walls of the groove for the purpose of preventing rotation of said ratchet 55 wheel while the pawl is being retracted.

In testimony whereof I affix my signature.
RALPH O. HELGEBY.
